Primary Examiner — Ramzi S Almatrahi(74) *Attorney, Agent, or Firm* — Michael Best & Friedrich LLP(57) **CLAIM**

We claim the ornamental design for a camera, as shown and described.

DESCRIPTION

FIG. 1 is a front perspective view of a camera showing our new design.

FIG. 2 is a front view of the camera shown in FIG. 1.

FIG. 3 is a rear view of the camera shown in FIG. 1.

FIG. 4 is a left side view of the camera shown in FIG. 1.

FIG. 5 is a right side view of the camera shown in FIG. 1.

FIG. 6 is a top view of the camera shown in FIG. 1; and,

FIG. 7 is a bottom view of the camera shown in FIG. 1. The broken lines depict portions of the camera in which the design is embodied that form no part of the claimed design.
